INVENTOR.
Chesley E. Osborn

BY *R. W. Smart*

ATTORNEY.

UNITED STATES PATENT OFFICE

CHESLEY E. OSBORN, OF PASADENA, CALIFORNIA

DESIGN FOR A LAMP GLOBE

Application filed March 14, 1930. Serial No. 34,872. Term of patent 14 years.

To all whom it may concern:

Be it known that I, CHESLEY E. OSBORN, a citizen of the United States, residing at Pasadena, in the county of Los Angeles and State of California, have invented a new, original, and ornamental Design for Lamp Globes, of which the following is a specification, reference being had to the accompanying drawing, forming a part hereof.

The drawing is a side elevation of a lamp globe embodying my invention.

I claim:

The ornamental design for a lamp globe as shown.

In testimony whereof I have affixed my signature.

CHESLEY E. OSBORN.
